UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

HEEL-BREASTING MACHINE.

1,169,125.

Specification of Letters Patent. Patented Jan. 25, 1916.

Application filed August 27, 1910. Serial No. 579,242.

To all whom it may concern:

Be it known that I, JAMES CAVANAGH, a citizen of the United States, residing at Boston, in the county of Suffolk and State 5 of Massachusetts, have invented certain Improvements in Heel-Breasting Machines, of which the following description, in connection with the accompanying drawings, is a specification, like reference characters on the 10 drawings indicating like parts in the several figures.

This invention relates to machines for use in the manufacture of boots and shoes and is herein shown and described by way of exemplification as embodied in a machine for 15 performing the breasting operation upon shoe heels.

The heels of shoes are usually composed of pieces of leather or leatherboard built up 20 roughly into the shape of the heel and, after attachment to the shoe, are surmounted by a top lift which is formed accurately to the shape which is to be given to the rounded or convexly curved portion of the finished heel. 25 The rounded portion of the heel is then trimmed off flush with the top lift leaving the front or relatively flat breast portion of the heel to be finished by a separate operation known as breasting. This operation is 30 usually performed by a knife arranged to reciprocate transversely of the plane of the shoe bottom and operated by the foot of the workman or from some other source of power. This operation is laborious, 35 especially when performed by foot power, and is slow since the shoe has to be jacked and firmly clamped in position to prevent the heel from being displaced by the resistance of the heel to the cutting action of the reciprocating knife. 40

One of the objects of this invention is to provide a machine for breasting shoe heels in the use of which the operator may hold the shoe in his hands and present it to the 45 machine for the breasting operation without the necessity of jacking the shoe as has hitherto been the usual practice.

One of the features of the invention is found in novel means with the aid of which 50 the shoe may be positioned, held and guided by the hand of the workman in a predetermined path while it is being presented to and acted upon by the relatively moving

cutting edge of a breasting knife. In the construction shown and described this means 55 comprises a novel organization of shoe resting mechanism arranged for movement to carry the shoe heel into and across the plane of action of the knife.

The knife has a continuous cutting edge, 60 and is herein shown as a belt knife which is held in extended position by suitable wheels or pulleys, preferably three, one at least of which is power driven, the pulleys being 65 preferably so arranged that the knife has one short horizontal run and two long runs. The knife is preferably driven at such velocity that a clean cut will be made through the shoe heel without greater resistance being offered on the part of the heel to the 70 breasting cut than can be readily overcome by the hand of the operator.

As a further feature of the invention the rest, which preferably engages the shank of the shoe near the heel, is arranged for movement so that the shoe may, after the usual curve of the shank has reached tangential 75 relation to the knife, be rolled, rocked or tipped so that all portions of the curve of the shank portion may be made to assume a 80 tangential relation to the curve of the knife for completely severing the chip from the breast portion of the heel. As herein shown and described, the rest is mounted upon inclined links so that it may be rocked or 85 tipped to continue the cutting operation of the knife about the curve of the shank, and the angular relation of the links may be varied to accommodate the rocking movement of the breast to different curvatures of 90 shoe shanks.

As a further feature of the invention the rest is constructed and arranged to engage the bottom of the shoe sole adjacent to the opposite marginal portions of the shank 95 portion thereof and to present clearance at the convex middle portion of the shank. By this construction, as the shoe is pressed against the rest the lateral sides of the shank portion are pressed against the last and 100 made to conform to the curve of the shank of the last to facilitate the separation of the chip from the breast along the line between the shank and breast. Furthermore a form of rest having this function, which may as 105 shown be formed with a V-shaped shoe en-

gaging surface, operates to restrain lateral movement of the shoe due to the drag of the knife.

These and other features of the invention will appear more fully from the following detailed description when read in connection with the accompanying drawing and will be defined in the appended claims.

In the drawings: Figure 1 is a general perspective view of a device embodying my invention, a portion thereof being broken away. Fig. 2 is a plan view of a portion of the device on a reduced scale. Fig. 3 is a sectional detail on the line *a—a* of Fig. 1.

In the drawings, 1 is a pulley on the shaft 2 which is journaled in a suitably supported frame 3. On the opposite end of the shaft 2 is a driving pulley 4 driven from any suitable source of power.

5 and 6 are idler pulleys disposed in the plane of rotation of the pulley 1. A belt knife 7 passing over these pulleys is held in extended position thereby in three straight runs and has its cutting edge disposed toward the observer in the view shown in Fig. 1. Extending over and behind the belt knife is a shield plate 8 covering part of the knife and forming a back stop. The plate where it is engaged by the knife is provided with a wall having a groove 9 to prevent displacement of the back of the knife. The front edges of the plate 8 are curved downward at 10 to form depending lips to protect the knife and prevent accidental displacement of the knife forwardly.

In front of the knife is a rest plate 12 which is guided for movement transversely of the knife by rods 14 and a tube 16, all of which are attached to the plate 12 and slide freely through holes in the frame 3 of the machine. The tube 16 is slotted at 18 and contains a spring 20 abutting against the tube at the forward end and at the other end engaging a stop 22, which passes through the slot 18 and engages the frame of the machine. The member 16 has a head 24 on its rear end which, in the forward position of the rest plate to which it is urged by the spring 20, engages the frame of the machine and prevents further movement of the rest plate in that direction. When the rest plate is moved rearwardly by pushing a shoe against the rest, the movement thereof is limited by the head 24 coming in contact with an adjusting screw 26 threaded through a bracket 28 extending from the frame of the machine.

Arranged upon the rest plate 12 is a rocking rest 30 which is V-shaped so as to engage the curved surface of the shank of a shoe in two separate lines for securely supporting the same. The rest 30 has members 32 pivoted by rivets 13 to its rear face, said members having ears pivotally connected by pins 31 and 33, links 38 and rods 35 to ears

34 and 36 on the plate 12. The ears 36 are not, however, directly on the plate 12 but are a part of a member 40 which has rods 42 attached thereto sliding in holes in the plate 12 and has a threaded rod 44 rotatably engaging it and threaded into the plate 12. By this means the distance between the lugs 34 and 36 may be adjusted and hence the amount of rocking movement of the rest 30 regulated. This rocking movement of the rest 30 is limited in each direction by stops 37 on the links 38 coming in contact with corresponding stops 39 on the plate 12, as is more clearly shown in Fig. 2, which represents in plan the relative positions of the rocking rest, the stops, the shoe and the knife. (The outline of the shoe is in dotted lines and the knife in dashed lines). The V-shape of the rest also enables the shoe to be readily held against displacement due to the drag of the knife upon the shoe during the breasting cut.

Provision is made for the vertical adjustment of the rest 30 by threading the rods 35 on the links 38 and having said rods rotatably journaled in the ears 34 and 36, thumb heads 46 being provided upon the lower ends of the rods. The links 38 are provided with brackets 41 integral therewith and depending from the same which are also integral with the collars 43 embracing the threaded rods 35. The collars 43 are spaced from the lower lugs 36 a sufficient distance to allow suitable vertical adjustment of the rocking rest. The rocking rest 30 extends normally somewhat above the base 12 and the adjustment described provides means for moving it vertically relatively to the knife so as to enable the operator to remove a predetermined amount of the heel breast which may be rested against the top of the rest 30 during the operation of breasting. By adjusting one of the screws 35 relatively to the other the rest may be inclined on the pivots 13 (see Fig. 3) to such an angle to the horizontal in either direction so as to enable shoes to be breasted rights and lefts.

In connection with the rocking rest 30 a relatively stationary rest 49 is provided for engaging the bottom of the shoe nearer the ball. This rest consists of a screw 47 threaded through a projection 48 on the plate 12 and having a head 49 provided with a friction plate 50 composed of rubber or other suitable material.

A guard 52 is provided to prevent the pieces of leather cut off from the heel from falling between the knife and the pulley.

The operation of the machine is as follows:—The knife being driven at high speed in either direction, the workman rests the shank of a shoe, the heel of which is to be breasted, against the rest 30, the latter being in its middle position with neither of the limiting stops 37 in contact with the corre-

sponding stop. In breasting straight heels the straight edge of the previously molded top lift of the heel may contact with the top face of the rest 12,—that is, the shoe may be 5 hung by its heel breast upon the said rest, the rest 30 being lowered sufficiently to act only as a shank rest. Thus used the relative vertical positions of the edge of rest 12 and the knife determine the depth of cut to be removed from the breast face of the heel. Or, if desired, the rest 30 may be adjusted into such a vertical and angular position as to cause the heel rested thereon to be breasted at a right or left inclination. The gage 30 10 may also, of course, be used in a horizontal position for breasting straight heels. The bottom of the shoe in all cases rests at the ball portion on the pad 50 of the adjustable rest 49. The shoe may also be positioned vertically by the eye so that the knife will just clear the top lift or will remove a small portion thereof, as desired. When properly positioned in any of the ways suggested, the workman pushes the shoe toward the knife 15 20 against the tension of the spring 20. The knife cuts through the heel until movement of the rest is stopped by the head 24 coming in contact with the stop 26 which is so adjusted that at this juncture the cutting edge 25 of the knife is tangent to the curve of the shank at its middle point but unsevered portions of the heel remain on each side of this point between the knife and the curved contour of the shank. The workman now rocks 30 35 or tips the shoe on the rocking support 30, thus bringing all portions of the curved line of cut on the shank portion tangent to the knife and completely severing the portion breasted from the heel. The forward pressure on the shoe against the spring 20 and 40 45 against the knife in the operation of feeding the shoe thereto serves so securely to hold the shoe in the V-shaped portion of the rest that no lateral displacement can occur due to the drag of the rapidly moving knife upon the shoe heel and, as the knife approaches the end of its cut, the rest is held by the now compressed spring 20 firmly against the lateral margins of the shank with substantial 50 55 pressure, thereby insuring that the sole shall be brought in contact with the wood of the last when the end of the breasting cut is reached.

To provide for different curvatures of the shank, the amount of rocking motion of the rest is adjusted by the screw 44 having a thumb head 54. The angle between the plane of the tread surface of the heel and the plane of the operating portion of the 60 knife or of the breast of the breasted heel (which is the same) may be adjusted by the screw 47 carrying the rest 49.

The angle which the plane of the tread surface of the heel makes with the breast is 65 determined, however, only in one direction

by the adjusted position of the stop 49; in the other direction it is determined by the position of the shoe laterally with respect to the stop 49 as determined by the relative adjustment of the screws 35. If the shoe is supported with the rest 49 to one side of the longitudinal median line thereof the plane of the heel breast will be correspondingly inclined to the longitudinal median line of the heel. It is customary to breast heels for 70 75 rights and lefts with these parts at an angle as suggested. The operator may breast rights and lefts by adjusting the inclination of the rest 30 so as to support the shoe first with the rest 49 to one side of the median line and then with it to the other side.

Having described and explained a machine embodying my invention in its preferred form, which embodiment may, however, be variously modified and is to be regarded as 80 for the purpose of illustration and explanation only, I claim as new and desire to secure by Letters Patent of the United States:—

1. In a heel breasting machine, breasting means comprising a knife and a tread rest 90 mounted for rocking movement about an axis perpendicular to the plane of the knife and arranged in proximity to and movable transversely of the knife edge.

2. A heel breaster comprising in combination an edgewise moving breasting knife, a V-shaped tread rest formed to engage the shank on two separate lines and supports under the ends of the rest permitting it to rock to bring opposite corners of the breast 100 against the knife alternatively.

3. A heel breaster comprising a belt knife, a shoe support, means for holding the knife in extended position with a portion thereof running transversely of a shoe on the support, a back guide for said knife presenting a bearing against the rear edge of the knife only and presenting an unobstructed space under substantially the full width of the knife, and means permitting and controlling the direction of relative movement of the support and knife in the plane of the knife.

4. A heel breaster comprising a belt knife, a shoe support mounted for reciprocation in the plane of the knife and for oscillation in a definite path, means for holding the knife extended in position with a portion transverse the longitudinal median line of the heel of a shoe on the support, means whereby the belt knife may be driven, and means preventing transverse movements of the knife.

5. In a heel breasting machine, the combination of breasting means and shank engaging means constructed and arranged to engage marginal portions only of the tread face of a transversely curved shank and adapted to apply substantial pressure to the marginal portions only of the tread.

- 4
- face of the shank during the operation of the breasting means.
6. In a heel breasting machine, an endless cutting edge, and a tread rest contacting with the shank portion of the shoe bottom, said rest being mounted for right line movement under the knife to cause the main body of the heel to be breasted and for lateral rocking movement under the knife 10 to cause the corners of the heel to be breasted.
7. A heel breasting machine comprising a belt knife, a shoe support mounted for movement only parallel to the plane of the 15 knife and in a rectilinear path, means for moving the knife transversely of the longitudinal median line of the shoe on the support, and means preventing transverse movement of the knife.
20. 8. In a heel breaster, a support adapted to engage the shank of a shoe, comprising a relatively stationary portion and a relatively rocking portion, said support being adapted for bodily movement in a plane 25 substantially perpendicular to the longitudinal median line of a shoe heel supported thereon, and a belt knife arranged for travel in proximity to the rocking portion of the support.
30. 9. In a heel breasting machine a cutting edge, means for positioning the shoe by engagement with the tread face of the sole and with the breast face of the heel relatively to said edge so that relative movement 35 between the edge and the shoe will breast the heel, means permitting such relative movement to bring the edge tangent to the curve of the shank, and means whereby further relative movement may be had 40 to bring other points of the curve of the shank tangent to the knife.
10. In a heel breaster, an endless knife, a support adjacent to said knife comprising a bed plate, guiding means for said plate 45 whereby it is adapted to move transversely of said knife and to pass therebeneath, a V-shaped rest on said plate adapted to receive the shank of a shoe, and links connecting said rest to said plate whereby it 50 is adapted for rocking movement relatively thereto.
11. In a heel breaster, an endless knife, a support adjacent said knife comprising a bed plate, guiding means for said plate 55 whereby it is adapted to move transversely of said knife and to pass therebeneath, a rest on said plate adapted to support the shank of a shoe at points on opposite sides of the medial line, and links connecting said rest to 60 said plate whereby it is adapted for rocking movement relatively thereto.
12. In a heel breasting machine, an endless knife, a rocking rest arranged for movement transversely of the operating portion 65 of the knife, means for adjusting the rock- 70 ing movement of the rest, and means for adjusting the angle between the plane of the top-lift of a heel to be breasted and the plane of the operating portion of the knife.
13. In a heel breasting machine, the combination with breasting means, of shank engaging means movable relatively to the breasting means and having its engaging face recessed to bear only on the lateral portions of the tread face of a transversely 75 curved shank and to apply substantial pressure to said portions during the relative movement of the shank engaging means and the breasting means.
14. In a heel breasting machine, an endless knife held in extended position and mounted for longitudinal movement, means for positioning a shoe in such relation to said knife that relative movement therebetween will breast the heel, means permitting 80 such relative movement, means whereby relative movement between the knife and the shoe may be had to bring the knife tangent to all points on the line of juncture of shank and heel breast and means for preliminarily 85 adjusting the angular relation between the plane of the tread surface of the heel and the plane of the operating portion of the knife.
15. In a breasting machine, a belt knife, 90 rotary means over which the knife passes, means to support a shoe and permit movement of the same in proper relation to the knife to breast the heel, and means located below said support and over said rotary 100 means to prevent the severed portions of the heel from falling between the belt and the rotary means.
16. A breasting machine comprising a frame, pulleys in triangular relation on said frame, a knife passing over said pulleys, a back stop for the knife, a work support movable at right angles to the operating run of the knife, front and back stops for the support, and means normally holding the support against the front stop. 105
17. In a heel breasting machine, a belt knife, three pulleys in triangular relation supporting the knife, a back guide for the knife, a plate mounted for movement transversely of the knife and perpendicular thereto, stops limiting the backward and forward movement of said plate, resilient means forcing the plate mounting against the forward stop, a rest member, and links connecting 110 said member to said plate.
18. In a machine of the class described, a band or belt knife, three pulleys arranged for supporting the knife with one short horizontal and two long runs, shoe positioning means disposed adjacent the short run of the knife and having a normal work receiving position in a plane below the knife and remote from the knife and movable in a plane 115 parallel to the knife to guide the shoe while 120

- it is being breasted, and means for guiding the positioning means parallel to the plane of the knife for the breasting operation and back to work receiving position after the 5 breasting operation.
19. A heel breasting machine, having in combination, a breasting knife and a shank rest which is mounted for right line movement with the shoe and relatively to the 10 knife in a plane under the knife to cause the main body of the heel to be breasted, and for lateral rocking movements under the knife to cause the corners of the heel to be breasted.
20. A heel breasting machine, having in combination, an endless knife and a rocking shank rest guided for right line movement with the shoe and relatively to the knife in a direction transversely of the operating portion 15 of the knife and arranged to tip laterally for severing portions of the heel remaining uncut during said right line movement.
21. In a heel breasting machine, a longitudinally movable knife having an endless cutting edge, means preventing lateral movement of the knife, supporting means mounted for movement transversely of the knife and parallel to the plane thereof, means for 25 arresting said movement to limit the breasting cut and shoe resting means mounted upon said supporting means for rocking movement relatively thereto.
22. In a heel breasting machine, a band 30 knife 7 and a shield 8 arranged to cover the knife and having clearance for presentation of the work to the knife and having at each side of said clearance the depending lips 10 to protect the edge of the knife.
23. In a heel breasting machine, a band knife 7 and a shield 8 arranged to cover the knife and having clearance for presentation of the work to the knife and at the back of 35 said clearance a wall for resisting pressure 45 against the knife.
24. In a heel breasting machine a band knife and a shield projecting forwardly over the knife and presenting a back stop for the cutting portion of the knife and 40 depending lips to protect the front edge of the knife at each side of the cutting portion.
25. A heel breasting machine having, in combination, a breasting knife and a work rest against which the shoe may be pressed 45 by movement in a direction transverse to the shoe for contact at a plurality of points on the bottom portion of the sole only, said rest being mounted for movement with the work toward and from the knife and for 50 movement while the work is in engagement with the knife for continuing the operation of the knife about the curve of the shank.
26. In a heel breasting machine a breasting knife, a rocking rest to engage the 55 shank of the shoe and movable with the
- shoe for the breasting cut and tipping to cause the corners of the heel to be breasted, and a stop coöperating with said rocking rest to limit the tipping movement.
27. In a heel breasting machine a breasting knife, means to engage the shank of the shoe and movable with the shoe for the breasting cut, and a stop coöperating with said shank engaging means to limit the depth of the breasting cut, said shank engaging means having provision for relative movement of the shoe and the knife to complete the severance of the stock at opposite lateral ends of the breast after engagement of said means with the stop. 70
28. In a heel breasting machine a breasting knife, and shoe shank resting means between which and the knife there is relative movement to effect the breasting operation, said shoe resting means having provision for a relative rolling movement of the shoe and the knife at the end of the breasting cut for the purpose described. 75
29. In a heel breasting machine a breasting knife having a straight cutting edge and shoe resting means against which the shoe bottom is pressed and between which and the knife there is relative movement to effect the breasting operation, said rest being mounted to permit a rolling movement of the shoe against the knife for continuing the breasting cut about the curve of the shank. 80
30. In a heel breasting machine, a belt knife having an upper, horizontal run, and shoe guiding means, said parts being arranged to occasion the breasting chips to fall from below said run of the knife, and a depending shield extending obliquely downwardly in position to guide the chips 90 from the moving parts of the machine. 100
31. A heel breasting machine having, in combination, a constantly running knife, and a rocking shoe rest automatically moved into a shoe receiving position remote from the knife, arranged to guide the shoe into and progressively across the path of said knife, to be moved for that purpose by force transmitted to it through the shoe from the operator and to be rocked to complete the severance of the chip at the sides of the shank. 110
32. In a heel breasting machine the combination with a breasting knife, of a shoe rest guided relatively to the knife for engaging throughout the breasting operation, with the tread face of the sole adjacent to the heel breast of the shoe, and means for relatively actuating the rest and the knife transversely of the shoe in a direction parallel with the plane of the sole during the breasting operation. 120
33. In a heel breasting machine the combination with a breasting knife, of a shoe rest guided relatively to the knife for en- 130

gaging throughout the breasting operation, with the tread face of the sole adjacent to the heel breast of the shoe, said rest and the cutting edge of the knife being mounted for operative movement in directions substantially perpendicular to each other.

34. In a heel breasting machine, the combination with a breasting knife of shoe resting means comprising a member for engaging the shank on opposite sides thereof only near the breast to force the shank portion of the sole against the last, and a member for engaging the bottom of the forepart over a limited area.

35. In a heel breasting machine the combination with a breasting knife, of shoe resting means comprising a member for engaging the shank upon opposite sides near the breast, and a sole forepart bottom engaging member, said members being relatively adjustable to vary the vertical inclination which shall be given to the breast face of the shoe heel by the breasting operation.

36. A heel breasting machine having, in combination, a breasting knife, and means for engaging the rough breast face of an attached heel to position the heel relatively to the plane of action of the knife and to determine the amount to be cut off from said rough face by the breasting operation, said means being constructed and arranged for adjustment angularly to vary the lateral angle of the breast face.

37. In a machine for breasting heels after they have been attached to shoes, the combination with a breasting knife, of means to engage the breast face of the attached rough heel and position the heel relatively to the plane of action of the knife for determining the amount to be cut off from the heel breast by the knife, and means 46 to adjust one end of said engaging means relatively to the other and to the knife to vary the angle with the plane of the knife at which the breast shall be cut.

38. In a machine for breasting heels after they have been attached to shoes, the combination with a breasting knife of means to engage the shoe bottom at the forepart at separated longitudinal lines on the shank and on the breast face of the heel to position the shoe angularly and longitudinally relatively to the plane of action of the knife.

39. In a heel breasting machine the combination with a breasting knife of a shoe positioning member constructed and arranged to engage the bottom of a shoe sole adjacent to the opposite edges of the shank portion thereof and presenting clearance for the convex middle portion of the shank.

40. A machine of the class described having, in combination, a breasting knife 7, a shoe rest 30 between which and the knife there is provision for relative movement to breast the heel, diverging links 38, and a

base 12 to which the links connect the rest for depression of its ends alternately in presenting the heel for severance of the stock at opposite lateral ends of the breast.

41. A machine of the class described having, in combination, a breasting knife 7, a shoe rest 30 between which and the knife there is provision for relative movement to breast the heel, diverging links 38, a base 12 to which the links connect the rest, and the screw 44 for adjusting the inclination of the links.

42. In a machine of the class described the combination with means for working on the shoe, of means for resting the shoe therefor comprising a support mounted on diverging links which are located at the opposite ends thereof and permit depression of either end of the support with simultaneous rise of the other end.

43. In a machine of the class described the combination with means for working on the shoe, of the rocking rest 30, the relatively inclined links 38, and the base 12 to which the links pivotally connect the rest substantially as described.

44. In a machine of the class described the combination with means for working on the shoe of means for resting the shoe therefor comprising a support mounted on diverging links which are located at the opposite ends thereof and permit depression of either end of the support with simultaneous rise of the other end, and means for adjustably limiting the described movement of the support.

45. In a heel breasting machine the combination with a breasting knife of the gage 12 to position the heel relatively to the plane of the knife, and the shank gage 30 carried by the gage 12 to limit the depth of the cut.

46. In a heel breasting machine, the combination of a knife operating in a horizontal plane and a locating and supporting rest upon which the heel may be hung by the heel breast to position it relatively to the knife for the breasting operation.

47. In a heel breasting machine, the combination of a knife operating in a horizontal plane and a locating and supporting rest upon which the heel may be hung by the heel breast and with which the shoe may be rocked relatively to the knife to sever the side portions of the chip along the intersection of the breast and shank.

48. In a heel breasting machine, the combination of a knife operating in a horizontal plane and a relatively stationary locating and supporting rest upon which the heel may be hung by the heel breast to position the shoe longitudinally with relation to the knife, and a relatively rocking shank rest to permit movement of the shoe for severing the corner portions of the chip cut from the heel by the breasting operation.

49. In a heel breasting machine the com-

- bination with a band knife and means for actuating it, of means to guide a shoe in a rectilinear path relatively to the knife for the breasting operation, including V-shaped
5 means to restrain the shoe from lateral displacement by the pull of the knife during the cutting operation.
50. In a heel breasting machine the combination with a band knife and means for
10 actuating it of means to guide a shoe for movement in a straight line relatively to the

knife for the breasting operation, including means engaging the shank of the shoe to restrain lateral movement thereof by the band knife.

15

In testimony whereof I have signed my name to this specification in the presence of two subscribing witnesses.
